UNITED STATES PATENT OFFICE.

CHARLES H. NORTON, OF WORCESTER, MASSACHUSETTS, ASSIGNOR, BY MESNE ASSIGNMENTS, TO CINCINNATI GRINDERS INCORPORATED, OF CINCINNATI, OHIO, A CORPORATION OF OHIO.

CENTERLESS GRINDING MACHINE.

Application filed June 28, 1922. Serial No. 571,456.

My invention relates to precision grinding machines and more particularly to a machine for grinding cylindrical pieces of work without the use of supporting centers.

5 The ordinary requirements for grinding small cylindrical objects include exceedingly fine limits of measurements and rapid, repeated duplication of accurately sized work. Owing to the time and expense involved in mounting such small objects as 10 rollers on centers, various types of centerless grinding machines have been devised but difficulties have been met in supporting the work accurately and maintaining it in correct position as grinding proceeds, as well as in the problem of truing the wheel.

One type of centerless grinding machine 20 has comprised opposed abrasive wheels, one utilized to grind the work and the other to rotate it. The work has been supported against these two wheels by a third flat part or a convex surface placed below the work and engaging it on substantially a line contact.

25 In the course of my experimentation, I have found it to be of advantage in a precision grinding machine of this type that the cylindrical work be so supported that it cannot vibrate or change its axial position while 30 rotating except as required by diminution in size as grinding proceeds and that irregularities of surface outline be ground out first to produce a cylindrical article before the final finishing operation can be effected.

35 To accomplish such an object, I employ a work supporting shoe which presents a concave instead of a flat or convex surface to the work, and preferably make this surface cylindrical and of a radius equal to the required radius of the finished piece of work. 40 With a rest of this type the work tends to seek the shape of its supporting surface, hence the irregularities of outline are removed first and the grinding proceeds until 45 the work just fits the curve of the shoe.

I have also found that in a machine of this type it is of some advantage that the work be supported by such a steady rest below a line joining the centers of the two 50 abrasive wheels, and that the wheels be so mounted as to permit them to be brought into contact for truing one another. This preferably takes place on a line passing through their centers and the normal line of

55 contact of the work with the grinding wheel in order that the grinding wheel surface may be formed exactly parallel on its grinding line of contact with that of the work. It is accordingly a further object of my invention to provide a construction which 60 accomplishes such ends and which will permit the abrasive wheels to be kept in true shape with the minimum of effort on the part of the operator.

As a further consideration, I propose to 65 maintain the axes of the work and its regulating wheel parallel and to utilize the grinding wheel for feeding the work longitudinally by relatively tilting the axes of the grinding wheel and the work, whereby the 70 work regulating wheel controls only the rotation of the work and the grinding wheel serves both to abrade the work and to move it axially at a rate which depends upon the angle of inclination. Precision feeding 75 mechanism is also provided for feeding the grinding wheel and work relatively toward each other and means are employed for moving the two abrasive wheels and the work 80 toward and from one another in order to provide for grinding work pieces of different sizes and to take up the wear of the abrasive wheels. Further objects of my invention are therefore to accomplish such results and to provide mechanisms so arranged 85 and coordinated in a unified construction that various sizes and shapes of work may be ground automatically at a rapid rate which may be varied depending upon the degree of accuracy and finish desired. 90

With these and other objects of my invention, as will be readily apparent in the following disclosure, my invention resides in the combination of parts set forth in the specification and covered by the claims appended hereto.

Referring to the drawings illustrating one embodiment of my invention in which like parts are indicated by like reference numerals:

Figure 1 is a right-end elevation of my centerless grinding machine, having parts broken away and omitted to show the construction more clearly;

Fig. 2 is similarly a front elevation showing particularly the work rotating wheel, its adjustable supports and driving mechanism;

10 Fig. 6 is a perspective detailed view of the steady-rest support for the work;

Fig. 7 is a sectional view taken approximately on the line 7—7 of Fig. 2, showing the manner of supporting the work rotating 15 wheel slide, but with the strut removed and work rotating wheel in truing position;

Fig. 8 is a sectional view taken on the line 8—8 of Fig. 2, showing the universal gear casing; and

20 Fig. 9 is a sectional view taken on the line 9—9 of Fig. 8, showing the mounting of the gear casing 90.

In accordance with one phase of my invention I provide a centerless cylindrical 25 grinding machine of the opposed wheel type in which the work is supported between the active faces of the wheels, and preferably the peripheries thereof, by means of a steady-rest which serves as the sole support 30 for the work and is constructed and arranged to support the work opposite the lines of contact with each wheel. This work support is preferably provided with a concave partial cylindrical surface, the 35 radius of which is substantially equal to that of the finished work, and it is so located and constructed that it will support the work in correct position for grinding and entirely without the aid of the opposed 40 abrasive wheels.

Another phase of my invention comprises utilizing the grinding wheel not only to abrade the work but to move it longitudinally, and to this end I maintain the work 45 axially parallel with the work regulating wheel and so support the grinding wheel and the work that their axes are held at a suitable angle, whereby one component of force produced by the rotating grinding 50 wheel serves to move the work axially. If desired the machine may be so constructed that this angle of inclination may be varied, but this refinement in construction as well as various adjustment features hereinafter 55 described may be omitted from the simpler types of machines designed for specific operations.

In order that the wheels may be trued, I provide means whereby they may be brought 60 into contact, and preferably at the same position as the normal line of contact between the grinding wheel and the work, the machine being so constructed that one of the wheels may be traversed across the face of 65 the other. Further details of a complete

machine embodying my invention may comprise slides or other constructions which permit adjustment between the two wheels and the work support to accommodate different sizes of work and to provide for moving the 70 work and grinding wheel relatively to feed the wheel into the work and to adjust for grinding wheel wear.

In the specific embodiment of my invention, illustrated in the drawings, I have 75 shown a centerless grinding machine having a two-part base, the part 1, upon which the wheel slide 11 carrying a grinding wheel 12 is slidably mounted, being preferably of standard construction as illustrated, 80 details of which will be found in my prior patents and which form no part of the present invention. Upon the front base 2 are mounted various slides forming a carriage 13 which adjustably supports the work-rotating abrasive wheel 14 in peripheral opposition to the grinding wheel 12. The wheel 14 is rotated slowly and controls the rotation of the work. Since the axes of the work and the work rotating wheel should 90 be parallel, I mount the steady-rest support 15 upon the carriage 13, the construction of the various parts of which will be later described, so that the work will be movable and tiltable with the work rotating 95 wheel.

The steady-rest comprises essentially a work supporting part of the required shape and material which, as illustrated in Fig. 6, may be a shoe 16 removably mounted by 100 means of a tongue and groove construction on the support 15. For the reasons outlined above, this shoe has a partial cylindrical surface of revolution 17 of a radius equal to that of the finished work, this surface in the form illustrated being bounded by noses 18 and 19 formed by intersection of the curved surface by the side surfaces of the shoe. These noses may be rounded and the side portions of the cylindrical work 110 supporting surface may be flared out so as to provide wide surfaces of contact for the work before it has been reduced to the required radius, or they may be otherwise suitably constructed. It however is to be 115 noted that in the ordinary use of this machine, the work may be and preferably is ground only a few thousandths of an inch at a pass, hence the rest is preferably made with a curvature equal to that of the finished work so that the work may be held axially alined and all vibration is prevented. The steady-rest shoe is so located that the work axis is below a line joining the centers of the wheels. This arrangement is 125 such that the centers of the wheels and the work are not in a diametrical plane of the work, and the angular relation of the lines of contact of the work with the two wheels and the work rest is such that a repetition 130

of an error in grinding will not occur at each revolution of the work. Moreover, the support is intended to fully support the work without the aid of the wheels, except as this is affected by the forces set up by the grinding operation. It will be apparent that the thrust of the grinding wheel is towards the support, while the regulating wheel tends to lift the work from the support, when rotating, but the work cannot shift from its grinding position if the wheels are located in the relative positions as shown. It will be seen also that the same arrangement of parts will hold good for any other positions of the wheels relative to the work support, since the chief function of the latter is to hold the work correctly located under the thrust of the grinding wheel.

The construction of the grinding wheel mount may be of any suitable type, and is illustrated substantially as shown in my prior Patent No. 1,261,156, dated April 2, 1918. The wheel 12 is mounted on a suitable spindle driven by belt 25 from the main drive shaft 26 in the base of the machine. In order to feed the grinding wheel toward and from the work as required during the grinding operation, I provide a suitable feed mechanism which may be of standard construction, comprising as illustrated a crank arm 30 mounted to rotate the shaft 31, the inner end of which is provided with a pinion 32, adapted to mesh with the gear 33. This gear is mounted on the forward end of a feed screw 34. The wheel slide, which is slidably mounted on the usual V and flat ways, is provided with a half nut 35 engaging the feed screw 34. Any movement of the crank arm 30 will rotate the screw 34 in one or the other direction and feed the grinding wheel toward or from the work as desired. In order to feed the wheel with precision, I may employ a suitable micrometer hand feed mechanism 36 such as described in detail in my prior Patent No. 762,838 dated June 14, 1904. It is to be noted that in the ordinary grinding operation in which but little stock is removed from the work, after the grinding wheel has once been positioned for a certain size of work the feed mechanism is necessary only to adjust the position of the wheel as it wears away.

The steady-rest shoe, as shown in Fig. 6, is made of considerable length relative to the size of the work, so that each piece may be moved axially during grinding to permit the machine to be fed continuously. A hopper device or chute of suitable construction (not illustrated) may be provided to feed the pieces 40 into the shoe groove 17. In the form illustrated, I utilize the principle that if the work is tilted relative to the grinding wheel, it will be automatically moved axially as it rotates. In a simplified construction, this work regulating wheel and work support may be built rigidly fixed at a desired angle, but where it is desired to vary the rate of axial travel, the construction shown in the drawings may be employed. To this end, I provide a slide 41 carrying the work rest and work regulating wheel with curved V and flat ways 42 and 43 respectively and mount them on corresponding ways on the machine base 2. In order to adjust the position of this arcuate slide 41 to angularly locate the work rotating wheel, I may provide a suitable hand operated construction, such as a screw and hand wheel, so but in the drawings I have merely shown for the sake of simplicity of illustration a pair of screws 44 which are screw threaded into the base 2 and passed through the elongated slots 45 in the slide 41, so that the work rotating wheel 14 may be tilted axially to the desired angle and then the screws 44 tightened to hold the slide in adjusted position. The axis of curvature of the ways on the base 2 coincides with the center line of the two wheels when the work rotating wheel is in the truing position or with the line between the centers of the work and the grinding wheel during grinding.

In the form illustrated, a second slide is mounted on the arcuate slide, which permits adjustment of the work and wheel 14 towards the grinding wheel. This construction comprises a slide 46 carrying a dove-tailed slideway 47 on its under side which rides on a corresponding slide member 48 on the upper part of the arcuate slide 41. Movement of the member 46 relative to part 41 is effected by means of the hand wheel 49 and the usual nut and screw arrangement 50 as shown in Fig. 5.

The slide 46 in the present embodiment, is provided with a dove-tailed slideway 51 upon which is adjustably mounted the slide 52, adapted to carry the work supporting steady-rest 15 and the support for the work rotating wheel 14. This slide 52 permits the work rotating wheel 14 to be adjusted laterally relative to the grinding wheel. This adjustment may also be accomplished by suitable mechanism, such as the screw 53 engaging internal threads 54 formed in the slide and actuated by hand wheel 55, the screw and support being provided with engaging collar and flange to prevent axial movement of the screw, as will be clearly understood. These slides for adjusting the position of the work and wheel 14 may of course be arranged and constructed in other ways within the scope of the principles underlying my invention, the above description being illustrative only.

The steady-rest support 15 is rigidly mounted upon the rear of the slide 52, but in order that it may be removed to permit

truing the wheels, I preferably form it as a separate piece having accurately planed surfaces 60 engaging similarly formed surfaces on an overhanging projection 61 of the slide 52. It is securely fastened in place by means of a bolt 62, so that the shoe 16 is maintained rigidly in position on a massive support which cannot vibrate or shift its position.

10 The work rotating wheel 14 is also carried on the slide 52 with its axis mounted parallel with that of the work. In order to accommodate different sizes of work it is necessary that the wheel and the work be 15 mounted for movement relative to each other. Also, since the work and its rotating wheel, in the operation of this machine, are tilted at some angle relative to the path of travel of the operative surface of the grinding 20 wheel to give the necessary feeding action by the grinding wheel, the grinding wheel should have a correctly concaved face so as to contact fully with the work as the latter passes across the face of the wheel. 25 I accomplish this by truing one wheel by the other with their line of contact exactly located where the work is normally ground. To this end, I mount wheel 14 pivotally so that it may be swung down to a position 30 where its axis is on a line with the normal center of the work and the center of the grinding wheel. Then, by traversing the slide 52 the work rotating wheel will pass across the face of the grinding wheel, the 35 two wheels will be trued simultaneously, the wheel 14 in a cylindrical shape and the grinding wheel 12 of the proper curvature to present a line contact across its entire face with the work during grinding.

40 In the construction illustrated, the wheel 14 is rotatably mounted in suitable bearings 64 on the slide 65. This slide is mounted to move in a dove-tailed slideway 66 on the member 67, which is mounted to swing about 45 the trunnion 68 supported from the slide member 52 by the bearing brackets 69. As shown in Fig. 7, the bearing brackets 69 and trunnion 68 are hollow and concentric with the work, so that the latter when ground 50 may be fed through them into a suitable receptacle. The slide 65 is adjusted by means of hand wheel 70, which operates the usual screw 71 fitted in threaded socket 72 in the member 67, the screw being fastened to slide 55 65 by an end cap plate 73 secured between a collar on the screw and the hand wheel 70, as will be understood by reference to Fig. 7. By this construction I may adjust the slide 65 upon its slideway and move the work 60 rotating wheel 14 toward or from the work so as to produce the desired driving effect.

In order to satisfy the requirements set forth above as to the relative positions of the work rotating and grinding wheels, the work 65 and the noses of the steady-rest shoe, I pref-

erably locate the work rotating wheel 14 as high as possible. To this end I provide a suitable means such as a strut 75 which is removably positioned between the under surface of member 67 and the slide 52. To accommodate different sizes of work, struts of different length may be used, although other constructions may obviously be employed to adjust the position of the work rotating wheel. As illustrated in the drawings, this 75 strut may comprise two brackets 76 and 77 connected by a link 78, pivotally mounted thereon. The bracket 76 may be secured by screws to the under side of the slideway 67 and the bracket 77 may be mounted for 80 movement transversely across the slide member 52, as shown particularly in Fig. 4. This lower bracket may be equipped with a tongue and groove construction 79 as illustrated and be held in adjusted position by means of 85 bolts 80 engaging nuts sliding in the T-slots 81. By means of this construction the single strut may be employed to accommodate various sizes of work by loosening the bolts and sliding the lower bracket to the desired 90 extent. When it is necessary to true the wheels the strut may be removed and the wheel 14 swung about the axis of its trunnion until the member 67 rests on the slide 52, after which the wheel 14 may be fed forward 95 by means of the screw feed hand wheel 70. Thereafter the wheel 14 may be traversed across the face of wheel 12 by turning the hand wheel 55. The steady-rest 15 will have been previously removed in order to permit 100 engagement of the wheels.

Since the wheel 14 must be rotated in various axial positions, I provide a suitable universal or flexible drive which will permit the wheel to be tilted axially as well as be 105 moved bodily in three directions as determined by the slides 46, 51 and 57. In my preferred construction, I employ spiral gearings mounted in universal casings and having a telescopic connection therebetween. As 110 illustrated, a gear casing 90 is pivotally mounted on the spindle 91 which carries the wheel 14, so as to swing thereabout. This spindle is provided with a spiral gear 92, meshing with a spiral gear 93 on the shaft 94. The gear casing 95 is pivotally mounted in the casing 90 as shown in Fig. 8 so that it 115 may swing about the axis of the shaft 94, thus permitting a universal movement. On the other end of shaft 94 I provide the spiral gear 96, which meshes with the spiral gear 97, mounted on the vertical shaft 98. In order to permit the desired movement of the work rotating wheel 14, I telescope the shaft 98 within the hollow shaft 100 keyed there- 120 to so that as the position of the work rotating wheel 14 is changed the shaft will lengthen or shorten as the case may be.

At the lower end of the shaft 100, I provide another set of universally swinging gear 125

casings like that shown in Fig. 8. This comprises a casing 101 supporting the lower end of the shaft 100 which has a spiral gear 102 keyed thereto and meshing with a gear 103 on the shaft 104, the casing containing these gears being mounted so that it may swing about the shaft 104 as a pivot. On the same shaft 104 I provide a spiral gear 105 meshing with the spiral gear 106 on the shaft 107 mounted in the machine base. The casing 108 mounted to swing about the shaft 107 carries the shaft 104 suspended therein. It will be readily seen from the disclosure that the above described driving mechanism will permit a universal motion of the work rotating wheel 14, so that any desired adjustment may be accomplished. The shaft 107 is provided with a spiral gear 110, which meshes with a corresponding gear 111 on the shaft 112. This shaft is also provided with a spiral gear 113, which meshes with a similar gear on the main drive shaft 26. The main drive shaft 26 and the shafts 112 and 107 are mounted for rotation in suitable bearings within the base.

To eliminate any undue strain upon the telescopic shaft 98-100, I provide a telescopic guide rod 115 which is pivotally mounted on the projections 116 of the casing 90 and the projections 117 of the casing 108. As the work rotating wheel 14 is moved to make the necessary adjustments, the guide rod will swing the casing 108 in accordance with the position of casing 90 and thus relieve the drive shaft 98-100 of the necessity to move the gear casing.

The grinding wheel 12 is driven at a fast rate of speed such as that used in a modern cylindrical grinding machine, but the work rotating abrasive wheel is preferably driven at a slow speed compared with that of the grinding wheel. The wheels are preferably rotated in the same peripheral direction, as shown by the arrows in Fig. 1, so that the faces of the grinding wheel and the work rotating wheel adjacent to the work will be traveling in opposite directions; the relatively slow speed of the work driving wheel will control the rotation of the work, thus permitting the proper grinding action upon the piece of work by the grinding wheel.

In the operation of my machine which will be obvious from the above disclosure, I first set the arcuate slide at the proper angle to give the desired feed to the work to be ground, then remove the strut 75 and swing the slide into the truing position and true the abrasive wheels. The member 67 is then placed at the desired angle, depending upon the diameter of the work. A steady-rest shoe having its bearing face of a radius substantially equal to that of the finished size of the work is located between the wheels, the work placed therein and the work rotating wheel 14 then advanced toward the work

so that it will contact with the work and impart the desired rotary motion to the same. The work rotating wheel 14 will of course be adjusted so that it is centrally located with respect to the grinding wheel 12 and 70 the grinding wheel is fed toward the work the desired amount. In order to adjust the grinding wheel to the proper position, a test piece of work is passed through the machine several times, the grinding wheel 12 being 75 fed forward after each pass until the right diameter is obtained. Then the adjustment mechanism 36 is properly set to locate the wheel, after which the machine is ready for use. The work is fed continuously into the 80 right hand end of the steady-rest and passes through between the two wheels which act upon the work as above described, the work rotating wheel 14 controlling the rotation of the work and the grinding wheel 12 performing the grinding operation and effecting also an axial movement or feed of the work along the work rest. From time to time, as the grinding wheel 12 wears away, it will be necessary to adjust the feeding 85 mechanism by moving the micrometer adjustment to permit the crank arm 30 to be rotated a short distance to take up the wear of the wheel.

As many possible embodiments may be 95 made of the mechanical features of the above invention, all without departing from the scope of the invention, it is to be understood that all matter herein set forth or shown in the accompanying drawings is to be interpreted as illustrative and not in a limiting 100 sense.

I claim:

1. A centerless grinding machine comprising a rotatable grinding wheel, a work regulating wheel rotatably mounted opposite thereto, means to rotate the grinding wheel rapidly and the regulating wheel slowly in order to respectively grind and rotate work positioned therebetween, and a work positioning member arranged and positioned to maintain a piece of work in operative contact with said wheels during the grinding operation, said member having an extensive concave cylindrical work positioning surface of substantially the same radius as that of the finished work.

2. A centerless grinding machine comprising rotatable grinding and regulating wheels whose peripheries are arranged close together, means to rotate the grinding wheel rapidly and the regulating wheel slowly, to respectively grind and rotate the work, and a member having a concave cylindrical surface of substantially the radius of the finished work arranged to position the work between and in operative relation to said wheels, the center of the work being out of line with the centers of the wheels.

3. A grinding machine comprising a ro-

tatable grinding wheel, a work regulating wheel peripherally opposed thereto, means to support the work regulating wheel with its axis in angular relation to that of the 5 grinding wheel, means to rotate the grinding wheel at a rapid rate and the other wheel at a slower rate to respectively grind and rotate the work, and a steady-rest to support the work between and in contact with the 10 wheels below a line connecting their centers which has a concave cylindrical surface of substantially the radius of the finished work which is so located as to hold the work axially parallel with the axis of the work regulating wheel.

4. A centerless grinding machine comprising a rotatably driven grinding wheel, an adjustably mounted, work regulating abrasive wheel, a movable work support between said 20 wheels adapted to hold the work against the wheel faces during the grinding operation but making contact there at a point offset from a line connecting the axes of the two wheels, and means for moving the wheels in 25 to engagement at the normal position of contact of the work and grinding wheel.

5. A centerless grinding machine comprising opposed rotatably driven, grinding and regulating wheels, a steady-rest removably 30 located therebetween to support the work in operative contact with said wheels, means to move said wheels relatively into truing contact and means for causing a relative traversing movement between the wheels 35 while in contact.

6. A centerless grinding machine comprising a rotatably driven grinding wheel, an adjustably mounted, work regulating, abrasive wheel peripherally opposed thereto, a work support between the wheels to hold the work in operative contact with the peripheries of said wheels, means permitting removal of the work support from between the wheels, means for moving the work 45 regulating wheel into engagement with the grinding wheel and means to traverse one of said wheels across the face of the other to true the surfaces thereof.

7. A centerless grinding machine comprising a base, a rotatable grinding wheel mounted thereon, a work regulating abrasive wheel peripherally opposed thereto, a slide carrying the regulating wheel which is movable parallel with the wheel axis, means to 50 rotate said wheels for all positions thereof, a removable support to hold the work in contact with the peripheries of the wheels, means for moving the work regulating wheel into contact with the grinding wheel, 55 and means for transversing the slide to true said wheels.

8. A grinding machine comprising a rotatable grinding wheel, a work regulating abrasive wheel peripherally opposed thereto, one of said wheels being axially tilted 60

relative to the other, means to rotate said wheels, means to support the work in peripheral contact with said wheels, means to move the wheels into contact at the normal position of contact between the work and the grinding wheel and means to traverse one of the wheels parallel with its axis to true the wheels. 70

9. A grinding machine comprising a rotatably driven grinding wheel, an adjustably mounted, rotatively driven, work regulating, abrasive wheel, means to support the abrasive wheel with its axis tilted with respect to the axis of the grinding wheel, a work rest positioned closely to the periphery 80 of the grinding wheel and supporting the work parallel with the axis of the work rotating wheel, and means for moving the work rotating wheel into contact with and traversing it across the face of the grinding 85 wheel to true the surfaces thereof. 75

10. A grinding machine comprising a rotatably driven grinding wheel, a movable support, a positively driven axially tilted, work regulating abrasive wheel mounted on 90 said support in peripheral opposition to the grinding wheel, a steady rest on said support having a concave cylindrical work supporting surface adapted to hold the work axially parallel with said abrasive wheel, 95 and means for moving said support and abrasive wheel and work thereon toward or from the grinding wheel. 90

11. A grinding machine comprising a rotatably driven grinding wheel, a positively 100 driven, work regulating abrasive wheel, a tilt-able support for the abrasive wheel mounted to tilt the abrasive wheel about an axis which cuts the line of contact of grinding wheel and work, a steady-rest on said support 105 having a concave, cylindrical, work supporting surface adapted to hold the work in contact with the wheels and axially parallel with said abrasive wheel, and means to feed the grinding wheel and work relatively 110 towards each other. 105

12. A centerless grinding machine comprising a base, a rotatably driven grinding wheel mounted thereon, a work regulating wheel opposed to said grinding wheel, a 115 member mounted on the base for arcuate movement about a line passing through the wheels and carrying said work regulating wheel, a slide mounted on said member arranged for movement toward and from the grinding wheel and a work rest mounted on the slide between the active surfaces of the 120 wheels. 120

13. A grinding machine comprising a rotatably driven grinding wheel, a rotatably 125 driven, work regulating abrasive wheel peripherally opposed thereto, a tiltable support for said abrasive wheel and a steady-rest mounted on said support to tilt there- with, said steady-rest having a concave 130

cylindrical surface located between the two wheels and adapted to support the work in contact therewith.

14. A grinding machine comprising a rotatably driven grinding wheel, a driven, work regulating abrasive wheel in peripheral opposition thereto, a slide arranged to support the abrasive wheel in tilted relation to the axis of the grinding wheel, a steady-rest on said slide having a concave cylindrical surface adapted to hold the work axially parallel with the tilted wheel and in contact with both wheels, and fine precision means to adjust the position of said slide.
15. A grinding machine comprising a base, a rotatably driven grinding wheel mounted thereon, a driven work regulating abrasive wheel peripherally opposed thereto, a slide mounted on said base which is movable in a plane tilted relative to the horizontal, a steady-rest on said slide having a surface for supporting the work in peripheral contact with the wheels, and a second slide mounted on the first slide and carrying said abrasive wheel for movement toward and from the steady-rest.

16. A grinding machine comprising a positively driven grinding wheel, a positively driven work regulating wheel opposed to the grinding wheel, a work support adapted to hold the work in contact with the wheels, a support for the work regulating wheel pivotally mounted to swing about the axis of the work and means for relatively moving said wheels toward and from each other in order to accommodate different sizes of work.

17. A grinding machine comprising a positively driven grinding wheel and a positively driven, work regulating abrasive wheel peripherally opposed to the grinding wheel, a support to hold said abrasive wheel in an adjustable position comprising a hollow trunnion and bearings axially aligned with the axis of the work and a work support adapted to hold the work in contact with the wheels, said hollow trunnion and work support forming a passage for the pieces of work.

Signed at Worcester, Massachusetts, this 22nd day of June, 1922.

CHARLES H. NORTON.
